PRECAST SWIMMING POOL

Ezra L. Culver, Florence, Ala.

Application February 9, 1956, Serial No. 40,101

Term of patent 14 years

(Cl. D34—5)

FIG. 1 -

FIG. 2 .

FIG. 3.

FIG. 5.

FIG. 6.

FIG. 4.

Figure 1 is a perspective view of a precast swimming pool showing my new design;

Figure 2 is a top plan view of the same;

Figure 3 is a bottom view of the same;

Figure 4 is a side view of the same;

Figure 5 is an end view of the same taken at the deep end; and

Figure 6 is an end view of the same taken at the shallow end.

The characteristic features of my design reside in the configuration of the deep end portion in its relation to and association with the other parts, as shown.

I claim:

The ornamental design for a precast swimming pool, as shown and described.
